UNITED STATES PATENT OFFICE.

LOUIS ARON BONHAM, OF ST. FRANCIS, WISCONSIN.

CRANK-PLATE FOR BOLSTER-SPRINGS.

SPECIFICATION forming part of Letters Patent No. 392,307, dated November 6, 1888.

Application filed August 3, 1888. Serial No. 281,842. (No model.)

To all whom it may concern:

Be it known that I, LOUIS ARON BONHAM, a citizen of the United States, residing at St. Francis, in the county of Milwaukee and State 5 of Wisconsin, have invented new and useful Improvements in Crank-Plates for Bolster-Springs, of which the following is a specification.

My invention relates to improvements in crank-plates for bolster-springs; and it consists 10 in a certain novel construction and arrangement of parts, fully set forth hereinafter in connection with the accompanying drawings, and specifically pointed out in the appended claims.

15 In the drawings, Figure 1 is a perspective view of the crank embodying my improvements applied in the operative position to a bolster, with the crank mounted therein. Fig. 2 is a longitudinal central sectional view of the same. Fig. 3 is a detail view of the improved bearing with the parts detached.

Referring to the drawings by letter, A designates the base-plate of the improved crank-bearing, on the upper surface of which is formed 25 a transverse wedge-shaped projection or rib, B, having a longitudinal groove, C, therein, which forms a half-bearing. The outer end of the base-plate is bifurcated to form the arms D D, which are adapted to pass on opposite 30 sides of the bolster-standard E, and the inner ends of the said arms are provided on their upper sides with the recesses or depressions F F.

G represents a cap-plate which fits over the base-plate, and is provided in its under side 35 with the V-shaped groove H, which is adapted to receive the wedge-shaped projection or rib B.

K represents a groove or half-bearing, which communicates with the groove H and registers 40 with the half-bearing C, thus forming, when in combination with the said half-bearing, a complete bearing, in which is mounted the crank L. The springs M M are connected to the ends of the said crank in the ordinary manner.

45 The inner side of the cap-plate is provided with the ears N N, having apertures n n, which register with similar apertures, a a, in the base-plate, and screws or bolts O O engage the 50 said apertures. The outer side of the cap-

plate is provided with ears P P, which fit in the recesses or depressions F F, and the ears and the plate are provided with registering apertures p and f, through which are passed suitable screws, P'. It will be seen that the 55 ears P P are flush with the upper side of the plate and fit tightly against opposite sides of the bolster-standard, and the outer side of the cap-plate is shaped to form a vertical bearing-face, Q, which bears against the inner side of 60 the standard.

The advantages of my invention are, it is easily and cheaply manufactured and strengthens the bolster-standard, all the wear is taken by the bearing and there is little or no chance 65 of breakage, and there is no risk of the crank being accidentally released from the bearing.

I am aware of the patents of A. J. Spalding (No. 287,063) and John Smith, (No. 287,335,) both of October 23, 1883, and I do not desire 70 to claim the construction shown therein.

Having thus described the invention, I claim—

1. The crank-plate comprising the base-plate provided with a transverse upwardly-tapered 75 rib having a half-bearing, C, in its upper side, and the cap-plate bearing on and affixed to the base-plate, and provided with a tapered groove fitting over the said rib, and a half-bearing, K, registering with the bearing C, in 80 combination with the crank mounted in the registering half-bearings and having bolster-springs connected thereto, substantially as specified.

2. The crank-plate for bolster-springs, comprising the base-plate provided with a wedge-shaped rib or projection having a half-bearing, C, the arms D D on the base-plate, passing 85 on opposite sides of the bolster-standard, the cap-plate fitting over the plate and provided with a V-shaped groove, H, fitting over the wedge-shaped rib or projection, and a half-bearing, K, registering with the half-bearing C, the ears N N on the inner side of the cap-plate, provided with apertures registering with 90 apertures in the base-plate, through which pass suitable screws, and the ears P P on the outer side of the cap-plate, fitting in recesses or depressions F F in the arms D D, and passing, respectively, on opposite sides of the 95 100

bolster-standard, the outer side of the said cap-plate being provided with a bearing-face, Q, to bear against the inner side of the said standard, in combination with the crank 5 mounted in the registering half-bearings and having the springs connected thereto, substantially as specified.

In testimony that I claim the foregoing as my own I have hereto affixed my signature in presence of two witnesses.

LOUIS ARON BONHAM.
